(57) **CLAIM**

The ornamental design for a hook, as shown and described.

DESCRIPTION

FIG. 1 is a perspective view of a first embodiment of a hook showing our new design;

FIG. 2 is a front view thereof, a rear view thereof being a mirror image of the front view;

FIG. 3 is a left side view thereof;

FIG. 4 is a right side view thereof;

FIG. 5 is an enlarged top view thereof;

FIG. 6 is an enlarged bottom view thereof;

FIG. 7 is a partially enlarged view showing the area "7" in FIG. 1;

FIG. 8 is a perspective view of a second embodiment of the hook;

FIG. 9 is a front view thereof, a rear view thereof being a mirror image of the front view;

FIG. 10 is a left side view thereof;

FIG. 11 is a right side view thereof;

FIG. 12 is an enlarged top view thereof;

FIG. 13 is an enlarged bottom view thereof; and,

FIG. 14 is a partially enlarged view showing the area "14" in FIG. 8.

The broken lines depict portions of the hook that form no part of the claimed design.

The dot-dash broken lines indicating an enlargement portion of the design form no part of the claimed design.

1 Claim, 14 Drawing Sheets
